UNITED STATES PATENT OFFICE.

HENRY L. DOHERTY, OF NEW YORK, N. Y.

METHOD OF CONDUCTING COMBUSTION.

1,145,357.

Specification of Letters Patent.

Patented July 6, 1915.

Application filed January 17, 1911. Serial No. 603,088.

To all whom it may concern:

Be it known that I, HENRY L. DOHERTY, a citizen of the United States, and a resident of New York city, in the county of New York and State of New York, have invented 5 certain new and useful Improvements in Methods of Conducting Combustion, of which the following is a specification.

My invention relates to a method of conducting combustion, and, in particular, to a method of conducting combustion in the heating flues of a coke-oven.

The object of my invention is to provide a method of conducting combustion in a coke oven or other furnace whereby a uniform 15 heating effect is secured from the top to the bottom of the oven and the maximum economy of combustion obtained.

My method consists in securing a prolonged combustion in the heating flues by burning a portion of the heating gas in the top flues with an excess of air and then adding to the stream of combustion products from the upper combustion flue, alternately, 20 an excess of gas and an excess of air, the proportion of the gas burned in the other flues being so regulated that a fairly uniform temperature is established in all the combustion flues, both the air and gas used 25 in the combustion being heated in separate recuperators by the hot products of combustion discharging from the heating flues.

In the accompanying drawings, I have shown a form of apparatus for applying my 30 invention.

Figure 1 is a longitudinal section through one set of heating flues and one set of recuperator flues and the gas producer on the line F, F^I, F^{II}, F^{III}, F^{IV}, F^V, F^{VI}, F^{VII} of Fig. 40. Fig. 2 is a vertical cross-section of one half of the apparatus on the line A, A^I, A^{II}, A^{III}, A^{IV}, A^V of Fig. 1. Fig. 3 is a vertical cross section of the other half of the apparatus on the line B, B^I, B^{II}, B^{III} of Fig. 1. 45 Fig. 4 is a similar section of one half of the apparatus on the line C, C^I, C^{II}, C^{III}, C^{IV}, C^V, C^{VI}, C^{VII} of Fig. 1. Fig. 5 is a similar section of the other half on the line DD' of Fig. 1. Fig. 6 is a horizontal cross-section on the line EE' of Fig. 1.

1 is the coking chamber or oven proper of the oven setting; 2 the gas producer; 3 the air recuperator; 4 the gas recuperator. 5 is the main combustion gas flue conducting 55 away the flue gases from a battery of ovens. 6^I, 6^{II}, 6^{III}, 6^{IV}, etc., are the heating or com-

bustion flues of the oven on one side and 7^I, 7^{II}, 7^{III}, 7^{IV}, etc., are the combustion flues of the other side of the oven.

8 and 8' are the gas up-take flues for the 60 two sides of the oven and 9 and 9' the air up-take flues.

10^I, 10^{II}, 10^{III}, 10^{IV}, etc., are the gas nostrils connecting the gas flue 8 with the combustion flues 6^I, 6^{II} and 6^{IV}.

11^I, 11^{II} and 11^{III} are the air nostrils connecting the air flue 9 with the combustion flues 6^{II}, 6^{IV} and 6^{VI}.

12^I, 12^{II}, 12^{III} are the gas nostrils connecting the gas flue 8' with the combustion flues 7^I, 7^{II} and 7^{IV}.

13^I, 13^{II} and 13^{III} are the corresponding air nostrils or ports for the side of the oven in which are located the combustion flues 7^I to 7^{VII}.

Dampers 14 and 14' provide a means for regulating the flow of gas through the gas nostrils, and dampers 15 and 15' a means for regulating the flow of air through the air nostrils.

The oven is symmetrical in all respects in relation to a vertical plane through its middle, so that the reproduction of both sides of the oven in the several views is unnecessary to a clear showing of its construction, 85 but numerals referring to the duplicate parts are introduced herein, for the sake of brevity and clearness in the description.

16 and 16' are flues through which combustion gases are drawn down from the flue 6^{VII}, under the action of the injectors 17 and 17' respectively, and forced under the grate of the producer 2.

18 and 18' are the side walls of the oven and 19 and 19' the end walls.

20 is the fuel chute of producer 2, 21' the ash door giving access to the ash pit 21 and the grate 21'' of the producer.

22 are the hand holes having covers 23 which provide access to the gas nostrils 10 and dampers 14.

24 and 25 are, respectively, the hand holes and covers of the air nostrils.

The air recuperator 3 comprises a series of flues 26 connected two in parallel so that the gas current passing through them is divided between two flues. The flues 26, in the form of recuperator shown, are built up from the arch 27 within the vertical flues 28, 28' and are spaced by the spacers 29. The ends of 110 the flues 28, 28' are closed by the special tiles 30 which are made to exactly fit the exterior

of the flues 26. There are thus formed two chambers into which the ends of the flues 26 open. Horizontal partitions 31 divide the chamber thus left in the front of the oven into three sections, 32, 33 and 34, which form the return connections for the flues 26, dividing them in effect into a return-bend flue composed of two parallel sections. The horizontal partition 35 forms the return-connection 36 for the upper flues of the recuperator at the rear. The partition 37 forms the return-connections 38 and 39 at the rear of the recuperator. Connecting with 38 is the passage 40, through which the products of combustion, which have passed through the gas recuperator 4, enter the chamber 38 and join the flue gases which have passed through the upper part of the air recuperator, the combined currents passing thence through the lower two divisions of the flues 26 of the air recuperator, and through 39 into the flue 41 leading to the main combustion gas flue 5. A tile, 42, serves, as a damper to the passage 41. The air enters the recuperator through the inlet passage 43 and passes back through the flue 44, whence it passes through the ports 45^I, 45^{II}, 45^{III}, 45^{IV}, into the main air flue 28. The air discharges from the flues 28 through the ports 46 into the air flue 46^a, thence into the uptake-flues 9 and 9' respectively, from which it passes through the respective air nostrils, 11^{II}, 11^{IV}, 11^{VI}, 13^{II}, 13^{IV}, 13^{VI}, into the respective combustion flues 6 and 7.

35 The construction of the producer gas recuperator is similar in principle to that of the air recuperator. Horizontal flues 47 provide a path for the passage of combustion gas through the recuperator. These flues 47 are built up from the producer arch 48 within the gas flue 51, being separated by the spacers 49. Tiles 50 prevent communication between the forward ends of the flues 47 and the producer gas flue 51. The chamber 52 forms a return-connection for the flues 47. The arch 53 forms the chamber 54 establishing communication between the inlet ends of the flues 47 and the lower combustion flue 6^{VII}. A tile, 67, serves to regulate the flow 50 of combustion gas from the flue 6^{VII} to the upper set of flues 47. Nostrils, 56^I, 56^{II}, 56^{III}, 56^{IV}, provide passage for the producer gas from producer 2 to the gas flue 51. A passage, 57, establishes communication between 55 the gas flue 66 and the gas up-take flue 8. Hand holes 58, with covers 59, provide access to the flues 47 of recuperator 4. Hand holes 60, with covers 61, provide a means of access to the flues 26.

60 The method of operation is as follows:—A bed of ignited fuel having been built up in the gas producer 2, air is discharged under pressure into the primary air flues 62 through the nozzles 63. Nostrils, 64, establish communication between the flue 62 and the ash-

pit 21 of the producer 2. Under the inductive action of the current of air discharging from 63 into the throat of injector 17, combustion gas is drawn down through the flue 16 from the lowest combustion flue 6^{VII}, 70 mingling with the air from nozzle 63, and the combined current of combustion gas and air passes through the flue 62 and nostrils 64 into the ash-pit 21 of the producer 2. Passing through the fuel bed 65 on the grate 21'', 75 the oxygen and carbon dioxide of the draft current react with the carbon of the fuel to form carbon monoxide according to the following reactions, viz.:

and

The producer gas passes through the gas nostrils 56^I, 56^{II}, 56^{III}, 56^{IV} into the producer 85 gas flue 51 of recuperator 4. During its passage through 51, the producer gas is heated by the sensible heat of the hot combustion gases passing through the flues 47. As I aim to operate my fuel bed at a comparatively low temperature, so as to avoid fluxing the ash of the fuel, the producer gas leaves the fuel bed at a temperature of from 1600–1800° F. The combustion gases, on the other hand, discharge from the flues 95 6^{VII} at a relatively higher temperature—say 2200° F. Even allowing for the necessity of a considerable temperature differential between the combustion gas and producer gas, there is thus a considerable range of 100 temperature—say, about 200–300° F.—through which it is practicable to raise the producer gas. The hot producer gas discharges from the flues 51 through the passages 66 and 57 into the flues 8, 8', passes up through the flues 8, 8', from which it passes through the several ports 10 and 12 in portions regulated by the dampers 14 and 14', respectively, into the combustion flues 6^I, 6^{III}, and 6^V, and 7^I, 7^{III}, and 7^V, where it 110 is burned. A portion of the hot products of combustion passing through the flues 6^{VII} and 7^{VII} is diverted into the flues 47 of each producer gas recuperator by opening the dampers 67 until the proper distribution of 115 the combustion products between the two recuperators has been obtained. The flue gases heating the producer gas recuperator pass through 54, 47 and the passage 40 and mingle with the stream of combustion gases 120 from the upper flues of the air recuperator in the chamber 38, the combined streams passing through the lower flues of the air recuperator and thence through the damped passages 39 and 41 to the main stack 125 flue 5. The relative proportions of the two streams of combustion gases passing through the two recuperators should be so adjusted that both streams reach the chamber 38 at approximately equal temperatures. 130

The upper heating flues 6^I and 7^I are heated solely by the sensible heat of the superheated producer gas introduced through the ports 10' and 12' respectively.

5 This portion of gas passes along the flues 6^I and 7^I to the other end of the oven. Here an excess of air is added in quantity sufficient to not only burn all of the gas passing into the flues 6^{II} and 7^{II} from the flues 6^I and 7^I, respectively; but also to burn about one-half of the gas which is added to the current at the inlet ends of the flues 6^{III} and 7^{III} through the gas ports 10^{III} and 12^{III}, respectively. The gaseous currents, now composed of combustion gases and an excess of producer gas, sweep through the flues 6^{III} and 7^{III} to the other end of the oven where an excess of air is added to the gaseous currents through the air nostrils 11^{IV} and 13^{IV}.

10 The proportion of air which is entered here should again be that which will not only burn the excess of combustible in the currents entering the flues 6^{IV} and 7^{IV}, but also about one-half of the gas which is to be admitted through the nostrils 10^V and 12^V, respectively. The burning gas sweeps through the flues 6^{IV} and 7^{IV}, and at the entrance to the flues 6^V and 7^V respectively, receives a fresh addition of gas through the respective nostrils 10^V and 12^V. The excess air entered through the nostrils 10^{IV}, 13^{IV} burns part of the gas entered through 10^V and 12^V, the gas currents sweeping through the flues 6^V and 7^V and into the flues 6^{VI} and 7^{VI}, respectively. At the entrance to 6^{VI} and 7^{VI} the gaseous currents receive their final portion of air through the nostrils 11^{VI}, 13^{VI}, the air admitted here being limited to that required to secure the excess necessary

15 to complete combustion. The gaseous currents after passing through the flues 6^{VI} and 7^{VI} should, in proper working, be composed only of products of complete combustion, nitrogen and a small excess of air. In the flues 6^{VII} and 7^{VII}, respectively, the combustion gases are divided, as before explained, part going to the producer gas recuperators and part passing through the passages 32 to the air recuperators.

20 In regulating the distribution of gas and air to the flues 6^I, 6^{II}, etc., and 7^I, 7^{II}, etc., it is my aim to so regulate the proportions in the several flues that an approximately uniform temperature is secured throughout each series of flues. While I discharge the combustion gases from the combustion or heating flues 6^{VII} and 7^{VII} at a comparatively high temperature (about 2000° to 2200° F.) I do not thereby withdraw the heat of these

25 gases from the system, since, by using both the producer gas and air to recuperate the heat of the combustion gases I am using, in the recuperators, currents of approximately balanced heat capacities. Therefore, I re-

30 turn to the combustion flues in the air and

producer gas the bulk of the sensible heat which is carried out of the flues by the hot combustion gases discharging therefrom, the exact proportion returned depending upon the efficiency of the recuperator used.

70 With a good efficiency in the recuperator, the gases discharged to the stack flue may be cooled to 200° to 300° F.

Having described my invention, what I claim is:

1. The method of conducting the combustion of gas, which comprises, instituting the combustion of a portion of said gas with a portion of air, and prolonging the flame of the initial combustion, by adding thereto, alternately, a further portion of gas and a further portion of air, the said further portions of gas and air being added at such intervals as to maintain the initial flame substantially continuous.

80 2. The method of conducting the combustion of gas which comprises, instituting the combustion of a portion of said gas with a portion of air in excess of that required to supply oxygen for the complete combustion of said portion of gas, and prolonging the flame of the initial combustion by a secondary combustion caused by adding thereto a further portion of gas in excess of the free air remaining in the flame gases from the initial combustion, followed by a further portion of air in excess of the unconsumed gas remaining in the flame gases from the secondary combustion.

90 3. The method of conducting the combustion of gas to secure a prolonged flame, which comprises, instituting the combustion of a portion of said gas with a portion of air in excess of that required to supply oxygen for the complete combustion of said portion of gas, and prolonging the flame of the initial combustion by a secondary combustion maintained by adding to the flame gases a further portion of gas in excess of the free air remaining in the said flame gases from the initial combustion, followed by a further portion of air in excess of the unconsumed gas remaining in the flame gases from the secondary combustion, and repeating the additions of gas and air, in like manner, until the desired prolongation of flame has been secured.

100 4. The method of conducting the combustion of gas, which comprises, burning a portion of said gas with a portion of air in excess of that required to supply oxygen for the complete combustion of said portion of gas, and adding to the so-formed hot gases a further portion of gas, followed by a further portion of air, each of said portions of gas and air added being of sufficient quantity to establish a momentary excess of gas or air, as the case may be, in the gas mixture.

110 5. The method of conducting the combustion of gas to secure a prolonged flame of

approximately uniform temperature which consists in burning a portion of the gas with an excess of air and then separately adding to the products of such combustion 5 a further portion of gas followed by a further portion of air, and repeating said operations, the volumes of the respective portions of gas and air being regulated to that required to maintain the temperature of 10 the stream of gases at, approximately, the temperature of the products of the initial combustion.

6. The method of conducting the combustion of gas, which comprises, preheating 15 said gas, burning a portion of the preheated gas with an excess of air and separately adding to the resulting hot gases, an excess of preheated gas followed by an excess of air.

7. The method of conducting the combustion 20 of gas which comprises preheating said gas and preheating air, burning a portion of the preheated gas with a quantity of preheated air in excess of that required for the complete combustion of said portion of gas, 25 and then adding to the so-formed mixture of hot gases additional portions of preheated gas and additional portions of preheated air, each addition of a portion of gas being followed by the addition of a portion of air, 30 each of said portions of preheated gas and air added being of sufficient quantity to establish a momentary excess of gas or air, as the case may be, in the gas mixture.

8. The method of conducting the combustion 35 of gas to secure a prolonged flame of approximately uniform temperature, which comprises, preheating said gas and preheating air by heat abstracted from the gaseous products of the combustion of said gas, 40 burning a portion of said preheated gas with a quantity of said preheated air in excess of that required for the complete combustion of said gas to establish an initial combustion, and then adding to the products of the ini-

tial combustion a plurality of separate portions of preheated gas and preheated air, the additions of said portions of preheated gas being alternated with the additions of said portions of preheated air, the volumes of the respective portions of preheated gas and preheated air being regulated to that required to maintain the temperature of the stream of flame gases at approximately the temperature of the products of the initial combustion.

9. The method of conducting the combustion of gas to secure a prolonged flame of approximately uniform temperature, which comprises preheating said gas, and preheating the volume of air required for the combustion of said gas, introducing a portion of the preheated gas into a relatively long combustion flue, introducing a portion of the preheated air in excess of that required to burn said portion of gas into said flue, 65 whereby an initial combustion is established in said flue, adding to the gases of the initial combustion at an intermediate locality in said flue, a further portion of gas in excess, following this addition of gas by adding a further portion of air in excess, at a locality further advanced along said flue, and repeating such additions of gas and air at regular intervals along said flue, the 70 volumes of the respective portions of preheated gas and preheated air being regulated to that required to maintain the temperature of the stream of flue gases at approximately the temperature of the products of the initial combustion.

Signed at New York city, in the county of New York and State of New York, this 16th day of January, A. D. 1911.
